Primary Examiner — Brett Miller*Assistant Examiner* — Rebecca Tsehay(74) *Attorney, Agent, or Firm* — Price Heneveld LLP(57) **CLAIM**

The ornamental design a washing machine, as shown and described.

DESCRIPTION

FIG. 1 is a front perspective view of a washing machine according to the design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of various features is for the purpose of illustrating portions of the article that form no part of the claimed design.

Dash-dot lines adjacent un-shaded areas represent bounds of the claimed design and form no part thereof.
